UNITED STATES PATENT OFFICE.

SEBASTIAN ZIANI DE FERRANTI, OF HAMPSTEAD, LONDON, ENGLAND.

TURBINE.

1,066,478.

Specification of Letters-Patent.

Patented July 8, 1913.

Application filed January 5, 1905. Serial No. 239,814.

To all whom it may concern:

Be it known that I, SEBASTIAN ZIANI DE FERRANTI, a subject of the King of Great Britain and Ireland, and residing at 31 Lyndhurst road, Hampstead, London, N. W., England, have invented certain new and useful Improvements in and Relating to Turbine-Engines, of which the following is a specification.

10 This invention relates to improvements in connection with the construction and operation of turbine engines generally, certain of these improvements being especially applicable to turbines of the isothermal type 15 with stage re-heating described in my application Serial No. 179407 of October 31st, 1903.

Figure 1 shows the application of a water gland to a turbine to reduce flow of heat to 20 the shaft bearing; Fig. 2 illustrates a method of supporting the turbine body on water cooled supports, Fig. 3 being a cross section taken on the line E F of Fig. 2; Fig. 4 shows an arrangement in which four pinions, each 25 driven by a separate turbine, mesh with a common gear wheel, Fig. 5 being a longitudinal section through such an arrangement and Fig. 6 being a sectional end view; Fig. 6^a shows a modification of the arrangement 30 shown in Fig. 6. Fig. 7 shows a method of applying the isothermal expansion principle to the case of turbines working on different shafts, while Fig. 8 shows a pressure flow turbine provided with an intermediate 35 re-heater.

I wish it to be understood that the drawings are of a diagrammatic nature throughout—individual pipes for example being in 40 many instances represented by a single line—and consequently should not be taken as working drawings.

In turbines such as I have described and in those of other types, it is often necessary to provide for temperatures in the turbine 45 up to say 400° C. In order to avoid cooling in the bearings, which would be ineffective or cooling right through the shaft, I prefer to put a water gland on the outside of the shaft between the bearing and the turbine. 50 Thus, as shown in Fig. 1, I form this water gland by means of a hollow casing, 2, encircling the shaft, 3, and with a packing, 4, at each side. A space, 5, is thus formed through which I circulate water under suitable pressure and so carry off the heat which would otherwise travel to the bearing. The water gland also has the effect where steam

is used of catching any leakage and condensing it or where a vacuum is applied of making a tight joint and preventing the inflow 60 of air to the turbine.

In turbines working at a fairly high temperature such as 400° C., it is important to prevent the flow of heat from the body of the turbine to the frame and bearings 65 and for this purpose I make the turbine body distinct from the rest of the structure and carry it upon feet of small section. I may also reduce the flow of heat by water jacketing these feet or the supports on 70 which they stand, thus keeping the frame and bearing cool over a long period of running. One method of carrying this part of my invention into effect is shown in Figs. 75 2 and 3. The turbine body, 6, is provided with a suitable number of feet such as 7, each resting on a pillar or support, 8. As shown in the section, Fig. 3, this supporting pillar at one point is made of a minimum cross sectional area consistent with strength 80 so as to reduce as much as possible the flow of heat across this section. As shown in the figure, I may provide the pillar with a water cooling arrangement, consisting of an inlet pipe, 9, leading to a chamber, 10, provided in the pillar, the water leaving this chamber by a tube, 11, surrounding the pipe, 9, and thence by way of the discharge pipe, 12. This water jacketing may be arranged 85 in series with the water glands already described.

Where I construct turbines of moderate power and it is desired to run the turbine wheels at speeds higher than those at which they can be conveniently used, I prefer to 90 make two or more separate turbines, such, as 13, Figs. 4 to 6, each having, for example, single or multiple impact reaction wheels. These separate turbines I group together 95 and fit the ends of their shafts with pinions, 100 14, which pinions I gear all into one wheel, 15, with a suitable gear reduction ratio to give the desired speed on this common shaft. As indicated diagrammatically in Fig. 6, the working fluid passes into the first 105 turbine by way of the superheater, 16, and after exhausting from this turbine passes into the second turbine through the re-superheater, 17, thence to the third turbine through the re-superheater 18, and so on 110 through the fourth turbine to the condenser, 19. A re-superheater may also be placed between the third and fourth turbines if desired according to the requirements of the

case and the exigencies of design. I thus employ the turbines in series, and provide superheaters between stages through which the steam may be passed as described in my 5 application Serial No. 179407 of 1903, in which this method of working is described in relation to single turbines, that is, turbines with multiple stages on one shaft. The turbines above described may also be 10 of the pressure flow type, provided that they are constructed so as to stand the temperature and may then also be coupled in series as in the case of the impact turbines. Turbines of moderate power may thus be 15 constructed in which each individual pinion, 14, need not transmit more than a fourth of the total power, the principal expense being in the large gear wheel, 15, which is common to the several turbines and 20 by which they are coupled together. It is of course permissible to couple the first two turbines in series and the third and fourth in parallel and in series with the first and second as shown in Fig. 6^a, so as 25 to give more conveniently a greater area for the low pressure steam. Or the first turbines may be impact reaction and the last turbines pressure flow. In all cases the coupling together for greater powers and 30 also the superheating and intermediate re-superheating will be very beneficial.

Where two or more turbines are coupled in series as regards the working fluid and are placed on separate shafts without being 35 directly coupled together and each does work such as driving one of the propeller shafts of a ship, I supply the first turbine with superheated steam and re-superheat the working fluid in between the turbines, so as 40 to obtain a good thermal efficiency and so as to increase the mechanical efficiency owing to working throughout with a dry fluid. In some cases each turbine besides being supplied with dry and highly superheated 45 steam from the superheaters as above described, may also be divided into two or more stages each fitted with re-superheaters. Thus, referring to Fig. 7, an example of this 50 part of my invention is shown, in which three turbines A, B, and C are separately mounted on shafts, 20, driving the propellers, 21. Taking the case of steam turbines by way of example, the steam from the boiler passes first through the superheater, 22, and thence into the first stage, A¹, of the turbine A; after partially expanding the steam passes thence by way of the re-superheater, 23, to the second stage, A², of the turbine, A, where a second partial expansion 55 takes place. The exhaust from turbine A, passes to the re-superheater, 24, and on issuing thence is divided into two parts, which pass respectively into the first stages, B¹ and C¹, of the turbines B and C. The exhausts 60 from the stages, B¹ and C¹, then unite and 65 from the stages, B¹ and C¹, then unite and

together pass through the re-superheater, 25, whence, dividing, the expansion is completed in the second stages, B² and C², of the turbines, B and C, the steam finally exhausting to the condensers, D. It will be 70 seen that in this example, the turbines, B and C, are in parallel as regards each other, but each is in series when considered with reference to turbine A.

Where I desire to re-superheat the steam 75 on its way through a pressure flow turbine, I divide up the space between the sets of blades, 26 and 27, (see Fig. 8) by means of circular rings (indicated at 28 in the figure) such as are now used on the balance pistons 80 of turbines of this type. The steam after initial superheating in the superheater, 29, passes through the first stage of the turbine and is then diverted by the rings, 28, through the re-superheater, 30, the expansion 85 being completed in the second stage.

I wish it to be understood that Fig. 8 is of a diagrammatic nature and only such parts of the turbine are shown as are necessary to illustrate this part of my invention, 90 the pistons, for example, used for balancing the axial thrust of turbines of this type being omitted.

Where turbines of the pressure flow type and employing re-superheating have to operate at anything less than full load, the pressure in the stages must be maintained by puff governing, as explained in my previous application Serial No. 282187, so as to get the fall of pressure in the turbine to 100 utilize the drop of temperature.

The above follows the principle of the isothermal expansion turbine engines described in my application Serial No. 179407, and is a particular application of the invention to divided turbines coupled in series as 105 regards the working fluid.

I am aware of the various patents, for example, No. 716468 of 1902, granted to the Honorable C. A. Parsons in connection with 110 turbines working on different shafts and do not claim anything therein described and claimed.

Having thus described my invention what I claim as new and desire to secure by Letters Patent is:—

1. The combination in a turbine of a casing; a main shaft passing through the ends of said casing shaft bearings external to said casing, together with fluid circulating 120 means disposed between said casing and said shaft bearings to lessen the flow of heat along said shaft.

2. The combination in a turbine of a casing within which the turbine proper revolves; a bedplate supporting said casing and separate therefrom together with means for retarding the flow of heat to said bedplate.

3. The combination of a turbine of a cas-

- ing within which the turbine proper revolves; supports for said casing together with fluid circulating means to cool said supports.
5. 4. The combination in a turbine of a casing within which the turbine proper revolves; a bed-plate and bearings separate from said casing together with supports for said casing and fluid circulating means to cool said supports.
5. The combination of a plurality of turbines working on separate shafts, certain of said turbines being divided into stages together with re-heaters disposed both between the stages of said certain turbines and also between certain of the individual turbines themselves, said re-heaters acting to keep the mean temperatures of said stages substantially the same as each other.
20. 6. The combination of a plurality of turbines working on separate shafts, certain of said turbines being divided into stages together with re-heaters disposed both between the stages of said certain turbines and also between certain of the individual turbines themselves.
7. The combination of a plurality of turbines working on separate shafts, certain of said turbines being divided into stages together with re-heaters disposed both between the stages of said certain turbines and also between certain of the individual turbines themselves, said re-heaters acting to render the expansion through said turbines on the whole substantially isothermal.
8. In a power installation, a plurality of turbine elements through which the working fluid passes in series, certain of said elements being of the impulse reaction type, while certain other of said elements are of the pressure flow type, shafts for said turbine elements, together with means for transmitting the power from said shafts to a common shaft substantially as described.
45. 9. In a power installation, in which the working fluid passes in series through a number of turbine elements, a plurality of impulse reaction turbine elements in the high pressure end of said installation, a plurality of pressure flow turbine elements at the low pressure end of said installation, shafts for said turbine elements, together with means for transmitting the power from said shafts to a common shaft substantially as described.
55. 10. In a power installation, in which the working fluid passes in series through a number of turbine elements, a plurality of impulse reaction turbine elements at the high pressure end of said installation, a plurality of pressure flow turbine elements at the low pressure end of said installation, means for reheating the working fluid be-
- tween said turbine elements, shafts for said turbine elements, together with means for transmitting the power from said shafts to a common shaft, substantially as described.
11. In a power installation, in which the working fluid passes in series through a number of turbine elements, a plurality of turbine elements of the impact reaction type at the high pressure end, a plurality of turbine elements of the pressure flow type at the low pressure end, a plurality of shafts for said turbines, pinions on said shafts, together with a common wheel with which said pinions gear, substantially as described.
70. 12. In a power installation, in which the working fluid passes in series through a number of turbine elements, a plurality of turbine elements of the impact reaction type at the high pressure end, a plurality of turbine elements of the pressure flow type at the low pressure end, a plurality of shafts for said turbines, pinions on said shafts, a common wheel with which said pinions gear, together with reheaters disposed between said turbines, substantially as described.
75. 13. In combination, a plurality of turbine elements, certain of said turbine elements being arranged in series, while certain other of said turbine elements are arranged in parallel in relation to the flow of working fluid, shafts for said turbine elements, together with means for transmitting the power from said shafts to a common shaft, substantially as described.
80. 14. In combination a plurality of turbine elements, certain of said turbine elements being arranged in series, while certain other of said turbine elements are arranged in parallel in relation to the flow of working fluid, shafts for said turbine elements, pinions on said shafts, together with a gear wheel with which said pinions gear, substantially as described.
85. 15. A turbine installation comprising in combination a plurality of turbine elements, certain of said turbine elements being arranged in series and certain of said turbine elements being arranged in parallel in relation to the flow of working fluid; means for reheating working fluid on its passage through the installation; shafts for said turbine elements; pinions on said shafts together with a gear wheel with which said pinions gear, substantially as described.
100. In testimony whereof I have signed my name to this specification in the presence of 120 two subscribing witnesses.

SEBASTIAN ZIANI DE FERRANTI.
